UNITED STATES PATENT OFFICE.

CHARLES ESCHER, OF JERSEY CITY, NEW JERSEY.

DESIGN FOR A TIRE TREAD.

Application filed March 27, 1925. Serial No. 12,915. Term of patent 14 years.

To all whom it may concern:

Be it known that I, CHARLES ESCHER, a citizen of the United States, and a resident of Jersey City, in the county of Hudson and State of New Jersey, have invented a new, original, and ornamental Design for Tire Treads, of which the following is a specification, reference being had to the accompanying drawings, forming part thereof.

Figure 1 is a fragmentary elevation looking toward the tread portion of the tire, showing my new design;

Figure 2 is a sectional view on the line 2—2 of Figure 1.

I claim:

The ornamental design for a tire tread, as shown.

CHARLES ESCHER.
